INVENTOR

GEORGE E. MARKS

BY Charles E. Bell

ATTORNEY

UNITED STATES PATENT OFFICE.

GEORGE E. MARKS, OF SOUND BEACH, CONNECTICUT.

ARTIFICIAL LEG.

Application filed April 16, 1924. Serial No. 706,829.

To all whom it may concern:

Be it known that I, GEORGE E. MARKS, a citizen of the United States, and a resident of Sound Beach, in the county of Fairfield and 5 State of Connecticut, have invented certain new and useful Improvements in Artificial Legs, of which the following is a specification.

The invention pertains more particularly 10 to artificial legs for amputations below the knee, and it consists in an artificial leg having, among other features, a knee-joint which may oscillate on the leg socket, the axis of motion preferably being in the region 15 of the ankle. One object of the invention is to provide an artificial leg which will afford better accommodation for long tibial stumps and in which the socket of the leg will move with the stump and maintain continuous 20 pressure at the places intended, thereby obviating constriction of the vascular parts back of the knee and other uncomfortable conditions.

Customarily artificial legs for tibial 25 stumps have knee joints riveted immovably to the leg sockets, the joints being constructed on the ginglymoid or unicentric plan.

In the natural knee, the knee articulation 30 is the result of the femur rolling on the irregular surface of the tibia, the movement being cycloidal or polycentric.

In requiring the polycentric natural knee joint to articulate with the unicentric artificial knee joint, there follows a movement 35 of the stump in the socket which induces unpleasant and painful consequences; the stump slips from its bearings and it oscillates from the front to the rear and back to 40 the front every time a step is taken, and when sitting the stump is influenced to recede from the front of the socket leaving a gap at the upper front edge of the socket and creating excessive pressure at the front 45 of the lower end of the stump and also on the tissues at the popliteal area or back of the knee joint. The undue pressure thus created at the popliteal area constricts the 50 blood vessels at the vascular part of the knee and hinders proper nourishment of the stump, thereby inducing swelling, congestion and laceration of the cicatrices.

One purpose of my invention is to obviate 55 the conditions just hereinbefore described by providing an artificial leg with the novel knee joint connection hereinafter described

which assures a proper yielding of the artificial leg to the varying polycentric lines of motion of the natural knee.

The invention will be fully understood 60 from the detailed description hereinafter presented, reference being had to the accompanying drawings, in which:

Fig. 1 is a side elevation of an artificial 65 leg embodying my invention, the position thereof indicating that the wearer is seated;

Fig. 2 is a corresponding view of the same as the leg appears when the wearer is in a standing position;

Fig. 3 is a transverse section, on a larger 70 scale, through the leg socket taken on the dotted line 3—3 of Fig. 1, and

Fig. 4 is a vertical section, on a larger 75 scale, through a portion of the leg taken on the dotted line 4—4 of Fig. 1.

In the drawings 10, 11, respectively, designate the leg socket and thigh corset of the artificial leg, these two features except as to certain details incident to my invention, being of usual or any suitable form and construction. The natural leg, or the remaining portion thereof, is indicated by 12.

My invention pertains to novel means for connecting the spaced-apart leg members 10, 11, and these means comprise, at each side of 80 the leg, a link 13 pivotally secured at its lower end to the leg socket 10 and extending at its upper end, above said socket, and a bar 14 connected with the thigh corset 11 and projecting beyond the lower edge of the 85 same and pivotally secured to the upper end of the link 13.

The links 13 at opposite sides of the leg socket 10 correspond with each other and are of metal and at their lower ends are secured 90 by screws 15 upon the polygonal ends 16 of a transverse spindle 17 confined within a stationary sleeve 18 crossing the interior of the leg socket, as shown in Fig. 3. The links 13 are adapted to have an oscillatory 95 movement, the axis of motion being at the lower ends thereof and preferably at the region of the ankle. During the oscillatory movements of the links 13 the spindle 17 turns in the sleeve 18, receiving its motion 100 from the links and assuring uniformity of motion in said links. My invention is not limited to the specific means shown for pivotally mounting the lower ends of the links 13. The links 13 at their upper ends 105 are forked or bifurcated, as at 19, Fig. 4, and receive between the members of the

forks the adjacent ends of the bars 14, the links 13 and bars 14 being pivotally connected together by screws 20 of familiar character.

5 The opposite sides of the leg socket 10 are vertically grooved, as at 21, to receive portions of the links 13 and permit said links to perform their oscillatory movements between the edge walls of said grooves, said 10 edge walls serving as stops for limiting the movements of the links and extending upwardly on diverging lines. Approximately near the upper end of the leg socket 10 I provide thereon an encompassing leather band 22 having at opposite sides of the socket, the loops 23 slit and bulged outwardly from said band and receiving and confining the upper portions of the links 13 without interfering with the oscillatory motion of 15 the links. The loops 23 confine the upper portions of the links 13 in correct relation to the sides of the leg socket, and during their oscillatory movements said links rub against the band 22 above and below the loops 23 instead of against the surface of the leg socket. The loops 23 also serve as means for limiting the extent of movement of the links 13.

30 The bars 14 are practically straight except at their exposed ends where they are slightly curved adjacent to the upper forked ends of the links 13, as shown, and said bars at their body portions are riveted to the thigh socket and concealed within elongated leather pockets 24 securely fastened to opposite sides of the thigh corset 11 and in 35 line with the length thereof.

40 In the use of the artificial leg having its members connected by the links 13 on the leg socket and bars 14 on the thigh socket, the human leg may have its natural movements both when the wearer is walking or taking a sitting position or arising to a standing position, without restraint and therefore without creating unpleasant or detrimental pressure either at the front of the 45 lower end of the stump or at the popliteal area. The oscillatory links 13 by being pivoted at their lower ends on the leg socket yield to the varying polycentric lines of motion in the natural knee, and hence the stump 50 may be firmly held in the leg socket, with-

out discomfort and with advantage to the wearer of the leg. My invention efficiently provides in the artificial leg a polycentric knee joint adapted to harmonize with the 65 polycentric joint of the natural knee and does so in a superior manner and by means which simplify the artificial leg construction, eliminating many rivets and other usual features. 60

The links 13 pivoted at their lower ends in the region of the ankle are features of special importance in carrying out my invention.

What I claim as my invention and desire 65 to secure by Letters-Patent, is:

1. An artificial leg, comprising a leg socket, a thigh member, links extending lengthwise of the leg socket and pivoted at their lower ends at opposite sides of the leg 70 socket for an oscillatory movement with respect to the leg socket, and bars on opposite sides of the thigh member pivotally secured to the upper ends of the links, whereby are provided jointed means connecting the 75 socket and thigh member at the knee.

2. An artificial leg as claimed in claim 1, in which the means securing the lower ends of said links to the socket member comprise a transverse spindle mounted in said member 80 and having polygonal ends on which the lower ends of the links fit and screws retaining the links on said ends, said spindle assuring uniformity of motion in said links.

3. An artificial leg as claimed in claim 1, 85 in which the socket member has vertical grooves on its opposite sides receiving said links, said grooves having upwardly diverging edge walls.

4. An artificial leg as claimed in claim 1, 90 in which the socket member has approximately near its upper end an encompassing band formed on opposite sides with outwardly bulged loops through which said links are strung and which retain the upper end portions of the links in proper relation to the 95 sides of the socket member.

Signed at New York city, in the county of New York and State of New York, this 14th day of April, A. D. 1924.

GEORGE E. MARKS.
